UNITED STATES PATENT OFFICE

FRANK C. WATSON, OF CHESTER, PENNSYLVANIA

ATTACHMENT FOR BOLT ACTION RIFLES

Application filed October 18, 1930. Serial No. 489,664.

This invention relates to attachments for rifles, and pertains particularly to an attachment for a bolt action rifle.

The primary object of the present invention is to provide an attachment for a bolt action magazine rifle whereby the same may be operated in the same manner as a pump gun.

Another object of the invention is to provide an attachment for bolt action magazine rifles which may be employed in connection with either the "lift up" or the "straight slide" type of bolt so that the user of the rifle may reciprocate the bolt for the removal of a shell and the insertion of a fresh cartridge without taking the rifle from his shoulder, the same as if the rifle were of the pump type.

Still another object of the invention is to provide an attachment of the above described character for bolt action magazine rifles, which may be applied without making any material alteration of the rifle structure.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a view in side elevation of a portion of a rifle showing the preferred form of the device embodying the present invention applied thereto.

Figure 2 is a bottom plan view of the rifle and attachment.

Figure 3 is an underside view of the attachment per se.

Figure 4 is a sectional view taken on the line 4-4 of Figure 2.

Figure 5 is a detailed sectional view through the rod guide.

Figure 6 is a view in side elevation of a portion of a rifle having a "straight slide" bolt showing a modified form of the attachment applied thereto.

Figure 7 is an underside view of the structure shown in Figure 6.

Figure 8 is a sectional view taken on the line 8-8 of Figure 6.

Referring more particularly to the drawings wherein like numerals of reference indicate corresponding parts throughout the several views, the numeral 1 indicates a bolt action magazine rifle wherein the barrel is indicated by the numeral 2, the forestock by 60 the numeral 3 and the breech and bolt by the numerals 4 and 5 respectively.

The rifle as shown is of the type employing a "lift up" bolt, this bolt having an arm 6 which, when shifted forwardly into the breech, is turned down into the recess 7 by which it is held in place.

It is, of course, well known that in the usual bolt action type of rifle, whether the same be of the magazine type or of the single shot type, the operator after firing the piece must lower it from his shoulder so that he may conveniently take a hold upon the bolt arm or lever 6 in order to lift it up and pull it back to effect the extraction of the shell and to permit a new charge to be shot into position after which the bolt is shoved forwardly and the lever turned down into the recess 7 which is formed in the breech for its reception.

With the device embodying the present invention the necessity for taking the gun away from the shoulder and lowering it in order to manipulate the bolt is done away with. This device comprises a hand hold or grip 8 which, as shown, is in the form of a longitudinally split or open cylinder. This grip receives the forestock 3 of the rifle and as the majority of rifles have the side faces of the forestock provided with longitudinally extending recesses or grooves 9 into which the finger tips of the user are engaged, the longitudinal edges of the grip may position in these grooves in the manner shown.

Attached at one end to the inner face of the hand grip 8 and extending longitudinally thereof is a rod 10, the forward end of which, or that end which is attached to the hand grip 8, is tubular to receive a support bar 11, the forward end of which is formed to provide the eye 12 which is secured to the rifle fore-

stock 3 by the screw 13 by any other suitable means.

The forward end of the rod 10 runs longitudinally of the under face of the forestock 5 of the rifle while adjacent its rear end is bent as indicated at 14 so that a substantial portion of the rear end 15 will be offset and positioned adjacent the side of the rifle in the manner shown. This offset portion 15 is slidably held in the guide 16 which is secured to the side of the rifle forestock at a point slightly forwardly of the recess 7 in which the bolt lever positions. Pivotally attached, as at 17, to the rear end of the bolt actuating rod 10 is an arcuate link 18 which is formed of a suitable springy or semi-stiff material and terminates in a hook 19 which engages over the bolt lever 6 from which it is prevented from disengaging by the head thereof which forms the usual part of this lever. The pivot 17 is covered by an extended portion 17' of the rod 10 to which it is attached so that the upward swinging movement of the link is limited. The guide 16 is so positioned that when the sliding hand grip 8 is shifted forwardly the end of the link 18 which is attached to the rod 10 will be drawn thereinto so that if the link has been swung upwardly upon the pivot 17, which is disposed at right angles to the path of movement of the rod and the bolt, when the end of the link is drawn into the guide, it will come into engagement with the rear edge thereof and downward pressure will be exerted thereon tending to swing it down from its raised position.

From the foregoing description it is believed that it will be clear that when the bolt is in position in the breech of the rifle for 40 the firing thereof, by drawing rearwardly upon the hand grip 8 pressure will be applied to the spring link 18 which, being resisted by the locking bolt lever, will cause the link to be bent or flexed so that an upward pressure will be exerted thereby upon the bolt lever. This will lift the lever out of the recess 7 and thus permit the bolt to be shoved rearwardly by the continued application of force to the rod 10. Upon reversely shifting 50 the rod 10 the bolt will be drawn into the breech until the lever 6 strikes the forward edge of the recess, whereupon the lower end of the link 18 will have passed into the guide 16 and, due to its curvature and its upwardly 55 swung position, the guide will apply pressure thereto so that it will be drawn downwardly and will thus draw the bolt lever down into the recess in which it positions to locate the bolt in place.

60 In Figures 6 to 8 there is shown a modification of my invention for use upon rifles having a bolt of the rectilineal or "straight slide" type. A portion of a rifle having a bolt of this character is shown and indicated generally by the numeral 20, the forestock of

which is indicated by the numeral 21, while the breech, the bolt and the bolt lever are indicated by the numerals 22, 23 and 24. The hand grip 25 is of the same construction as the hand grip 8 and has secured to the inner face thereof one end of an operating rod 26, the forward end of which receives the supporting rod 27 which is secured to the forestock of the rifle as indicated at 28.

The forward end of the rod 26 is disposed longitudinally beneath the underside of the forestock and suitable bends are made therein as indicated at 29 and 30 to position the intermediate portion 31 of the rod along the side of the forestock and position a portion of the rear end in spaced parallel relation with the side of the forestock adjacent the bolt 23, as indicated at 32. The offset rear end portion 32 of the rod 26 is suitably secured to the bolt lever 24 as, for example, it may be screw threaded to receive the holding nuts 33 which, after passing the end of the rod through an aperture formed in the bolt lever, may be drawn up against opposite faces of the lever to securely connect the rod and lever together.

In order to indicate to the user of the rifle when the bolt is in the proper position for firing and also in order to hold the bolt and operating mechanism therefor against movement there is secured to the side of the forestock, a strap spring 34. The forward end only of this spring is secured against movement as indicated at 35, while the rear end is bifurcated, as at 36, to slidably receive the shank of a screw 37, the head of which overlies the furcations to prevent this end of the spring moving away from the stock of the gun. Intermediate its ends the spring 34 is bent so that it is substantially V-shaped and stands away from the forestock out of contact therewith except at its ends, and at the forward side of the bend the spring is provided with a transverse notch 38.

The bolt actuating rod 26 carries a pin 39 which, in moving the bolt forwardly to position in the breech of the gun, rides up onto the rear end of the spring 34, passing over the bend thereof and finally positioning in the transverse notch 38 when the bolt has reached its seat.

In order to make it possible to operate the bolts of the rifles shown, the hand grip portion 39' of the stock must be slightly cut away as indicated at 30 so that the bolt will pass over the thumb of the user of the gun. In order to make the grip of the user more effective the portion 39' of the stock may have added thereto the inclined hand grip 41 which thus gives a pistol grip to the stock.

In connection with the form of the present invention illustrated in Figures 1 and 2, there is shown a device 42 which may be used to support the rod 15 when it is moved rearwardly. This device is in the form of a

bracket having a vertical portion which is secured to the side of the gun stock and a lateral portion over which the rod slides when retracted, as indicated in dotted lines in Figure 1.

From the foregoing description it will be readily apparent that with an attachment of the character herein described upon a bolt action magazine rifle, the rifle is transformed into a pump gun and the bolt may be freely operated without removing the rifle from the shoulder.

Having thus described my invention, what I claim is:

1. An attachment for a magazine rifle having a bolt of the "lift up" type, comprising a reciprocable member mounted upon the forestock of the rifle, guide means for said member, and a resilient link connecting said member with the bolt whereby oscillatory and reciprocatory movements are imparted thereto upon the movement of said member.

2. An attachment for a magazine rifle having a bolt of the "lift up" type, comprising a rod mounted for reciprocal movement upon the forestock of the rifle, guide means for said rod, and a curved resilient link having pivotal connection at one end with said rod and having the other end connected with an arm of the bolt.

3. An attachment for a magazine rifle having a "straight slide" bolt, comprising a reciprocable rod mounted upon the forestock of the rifle, means for connecting one end of the rod with an arm of the bolt, and means for effecting a latching engagement between the rod and the forestock of the rifle when the bolt is in operative position.

4. An attachment for a magazine rifle having a bolt of the "straight slide" type and having a manipulating arm or lever, comprising a rod mounted for reciprocatory movement on the rifle forestock, a hand grip connected with said rod, means for connecting the rod

45 with said bolt arm, a pin carried by the rod, and a resilient keeper element carried by the gun forestock for receiving said pin when the bolt is in operative position.

5. An attachment for a magazine rifle having a bolt of either the "lift up" or "straight slide" type, comprising a hand grip in the form of a split tubular body encasing a portion of the forestock of the rifle, a rod having a tubular forward end attached to said hand grip for movement therewith longitudinally of the rifle, means for connecting the other end of the rod with the rifle bolt whereby reciprocal movement may be imparted thereto, and a bar secured at one end to the forestock and slidably extended into the tubular forward end of said rod to slidably maintain the same in position.

6. An attachment for a bolt action rifle having a forestock provided with longitudinal grooves in the side faces thereof, consist-

ing of a hand grip in the form of a longitudinally split tubular body receiving the lower portion of the forestock and having its edges slidably engaged in said grooves, an elongated supporting member secured at one end to said forestock and having sliding connection with the hand grip, and a rod connected at one end with said handgrip and having its other end connected with the bolt of the rifle to shift the same when the hand grip is shifted.

7. An attachment for a bolt action rifle having a bolt of the "lift up" type, comprising a hand grip slidably mounted upon the forestock of the rifle, a rod member having connection at one end with said hand grip, a guide sleeve attached to the stock of the rifle and having the other end of said rod slidably mounted therein, and a link member pivotally attached at one end to the said other end of the rod and having its other end connected with the rifle bolt, said link member being curved and the said pivotal connection between it and the rod entering said sleeve when the bolt is in locked position.

8. An attachment for a bolt action rifle having a bolt of the "lift up" type, comprising a hand grip slidably mounted upon the forestock of the rifle, a rod attached at one end to said hand grip and extending rearwardly therefrom, a guide sleeve having the rear end of said rod slidably mounted therein, a curved link member of resilient material having pivotal connection at one end with the other end of said rod and having its other end attached to the bolt, said pivoted end of the link being drawn into said sleeve for the engagement of the link therewith when the bolt is in locked position, and a supporting plate member secured to the rifle stock rearwardly of said sleeve arranged to have said rod ride thereover.

In testimony whereof I hereunto affix my signature.

FRANK C. WATSON.
